UNITED STATES PATENT OFFICE.

EDWARD J. MOUNTAIN, OF NEW YORK, N. Y.

LAST.

1,094,739.

Specification of Letters Patent. Patented Apr. 28, 1914.

Application filed March 29, 1912. Serial No. 637,245.

To all whom it may concern:

Be it known that I, EDWARD J. MOUNTAIN, a subject of the King of Great Britain, residing at No. 175 West Seventy-third street, in the city, county, and State of New York, have invented certain new and useful Improvements in Lasts, of which the following is a specification.

My invention relates to lasts used in the manufacture of shoes, and the particular objects of my invention are to provide a last on which a shoe may be formed which will be a great comfort to the wearer, and assist in the correction of anatomical imperfections or injuries to the feet, particularly to permit the construction of a shoe which will close: than heretofore approximate to the formation of the foot of the wearer, permit flexibility in the parts where flexibility is needed, and supply rigidity and support to those parts where such characteristics are desired.

Usually lasts have been made where the bottom of the sole or heel or both are substantially flat in cross-section, and provision has not been made for all of the natural or, in some cases, abnormal curves and shapes of the foot. My invention is intended to supply this deficiency and to produce a last having the qualities above mentioned.

My invention is clearly set forth in the description, specified in the claims and illustrated in the drawings, in which drawings like symbols of reference indicate similar parts throughout the respective views.

Figure 1 is an elevation of my improved last, showing the inner side; Fig. 2, an elevation of the outer side; Fig. 3, a rear end view; Fig. 4, a front end view; and Fig. 5, a plan view.

Referring to the figures, 1 is the last as a whole.

2 represents a concavity at the point where in a shoe made on such a last would be the first phalanx bone of the normal foot. This concavity in the last of course produces or assists in producing a corresponding convexity in the insole of the shoe formed thereon, and the resulting convexity serves to support the great toe and enables it to flex, whereas a shoe formed on the ordinary last and having no such provision is liable to

cause "extension" and breaking down of the joint.

3 is a convexity on the outer side of the last to provide space for the great tuberosity of the fifth metatarsal bone, and thus provides in the shoe made on this last space and opportunity for the arch to assume and retain its normal convexity upward and outward.

4 is the convexity of the heel portion of the last.

5 is the concavity or hollow in the sole extending transversely across the last.

6 is the longitudinal arch on the inner side corresponding to what is known as the "hollow" of the foot.

7 is a convexity on the inner side of the last to provide space in the shoe for the internal cuneiform and the scaphoid bones of the foot, and to thus provide in the shoe made on the last opportunity for the arch of the foot to assume and retain its normal convexity upward.

Most lasts permit the manufacture of the conventional or standard shoe, usually having a flat sole and heel and without special provision for abnormalities, or for correcting abnormalities. In many cases a shoe made on such a last is uncomfortable and positively injurious to the wearer, especially if the foot is abnormal or injured, as by breaking down of the arch commonly called "flat foot," and particularly where artificial support to the arch is inserted or embodied in the shoe. In such latter cases the bones of the foot are raised and need space to take a normal position, especially those bones known as the fifth metatarsal and the internal cuneiform. Moreover, if the first phalanx bone is not supported as I have indicated, flexibility is diminished or made difficult and injury to the joint is liable to result.

I do not limit myself to any particular proportion or type of last, or method of construction, as these may be varied without departing from my invention. But

What I do claim and desire to protect by Letters Patent, is:—

1. A last for shoes having a concavity under the part corresponding to the first phalanx bone of the great toe, and a convexity

at the part corresponding to the location of the great tuberosity of the fifth metatarsal bone.

2. A last for shoes having a concavity under the part corresponding to the first phalanx bone of the great toe, and convexities at the parts corresponding to the location

of the great tuberosity of the fifth metatarsal bone and the internal cuneiform and scaphoid bones.

EDWARD J. MOUNTAIN.
